UNITED STATES PATENT OFFICE.

CHARLES F. STODDARD, OF BOSTON, MASSACHUSETTS.

NOTE-SHEET FOR MUSICAL INSTRUMENTS.

1,304,117.

Specification of Letters Patent.

Patented May 20, 1919.

Application filed January 23, 1912, Serial No. 672,802. Renewed October 24, 1918. Serial No. 259,595.

To all whom it may concern:

Be it known that I, CHARLES F. STODDARD, a citizen of the United States, and a resident of Boston, county of Suffolk, and State of

5 Massachusetts, have invented an Improvement in Note-Sheets for Musical Instruments, of which the following description, in connection with the accompanying drawings, is a specification, like characters on the 10 drawings representing like parts.

This invention relates to note sheets for governing the playing of automatic or partly automatic musical instruments, as, for example, player-pianos.

15 Among other objects the invention is intended to provide for a substantially accurate reproduction or imitation of the sustaining pedal effects produced in manual playing and to which the beauties of manual 20 rendition are largely attributable.

Heretofore in the art, provision has been made in automatic playing apparatus for operating a damper or similar pedal mechanism automatically under the control of the 25 note sheet. For example, marginal perforations in note sheets have been provided for shifting the damper rail of the instrument to withdraw the dampers and return them to the strings at desired intervals. This has 30 required the provision of a special mechanism additional to that required for sounding the notes.

Furthermore, in the art, provision has been made in automatic playing apparatus 35 for a manual control of the damper pedal mechanism such that the operator, following the instruction of notations upon the perforated note sheet, could withdraw and replace the dampers at will. This was objectionable because of the difficulty which 40 any operator but a skilled demonstrator finds in following the instructive notation on a note sheet and further, because it required the operator's attention to a manual 45 control additional to such tempo and intensity controls as are ordinarily operated manually on many types of players.

There is a further objection to any mechanism for operating a damper rail so as to 50 withdraw all or a large proportion of the dampers simultaneously, particularly in that the undamping of many notes including a succession of notes in the range permits sympathetic vibration of all of the un- 55 damped strings whether they are inharmonious or not. Thus, for example, when

all of the dampers are removed and only a few notes sounded, a sympathetic vibration is set up in substantially all of the strings and the resultant volume of sound is made 60 up of a combination of harmonious and inharmonious sounds such that the resultant sound is often harsh and disagreeable.

The specific embodiment of this invention about to be described overcomes all the objections referred to above and provides a note sheet capable of reproducing or imitating with remarkable fidelity the desirable effects which accompany the operation of a damper or similar mechanism, to the exclusion of 65 the inharmonious and undesirable effects. For this purpose, the illustrative note sheet does not necessarily have any marginal perforations for controlling any pedal operating mechanism, but may be provided 70 merely with perforations corresponding to the individual notes to be sounded. Furthermore, the illustrative note sheet provides for sustaining the individual notes just as they would be sustained by withdrawing the 75 damper pedal but without permitting the sympathetic vibration of any strings except those corresponding to the notes desired to be sounded.

For the first time in the art, this invention 85 provides for sustaining with the effects of a sustaining pedal operation, only selected notes to the exclusion of those which are not desired to enter into the harmony. Likewise, for the first time in the art, this invention 90 provides for a very beautiful reproduction or imitation of damper pedal effects by utilizing merely the individual note sounding actions of the instrument, thus providing for automatic production of 95 damper pedal effects upon instruments which have no automatic damper pedal mechanism or manual damper pedal mechanism for that matter. In these respects, therefore, applicant is entitled to be considered a pioneer inventor. 100

The character of the invention may be readily understood by reference to the accompanying drawing which shows diagrammatically and by way of illustration, a note 105 sheet embodying the invention. The arrow near the foot of the figure indicates the direction in which the note sheet is assumed to be traveling.

The perforations in the drawing, indicated in full lines, are those which would be 110 cut in accordance with practices prior to this

invention, for playing the individual notes, the sheet being laid out and the perforations arranged by reference to a musical score or other record of a composer's composition or 5 a performer's rendition. The dotted line prolongations of the full line perforations are those which contribute principally to the production of the sustaining pedal effect in the playing as controlled by the illustrative 10 note sheet.

According to practices heretofore employed, the note sheet would be cut as indicated in full lines, the advance ends of the different perforations being appropriately related to produce the desired tempo 15 as is well understood in the art. The lengths of the full line perforations would be determined substantially by reference to what may be called the "noted tempo value" 20 indicated upon the record from which the note sheet is made. In some instances, according to the prior art, one such full line perforation might be made to overlap the following perforation or perforations very 25 slightly in an attempt to produce what is called a legato effect, but the overlapping for this purpose would not cause any perceptible or material overlapping in the sounded tones; and the purpose of the 30 present invention is very different in kind from that of the so-called legato cutting.

In a note sheet cut in accordance with the full line representations of the drawing, no damper pedal or like effects could be produced automatically except by providing 35 supplemental perforations requiring the co-operation of automatic damper rail controlling mechanism, involving not only the provision of additional automatic apparatus 40 in the playing instrument, but also involving the sympathetic vibration of discordant strings.

In accordance with the present invention, however, the full line perforations are arbitrarily prolonged to sustain their notes regardless of the noted tempo values thereof but in accordance with the pedal effect desired to be reproduced or imitated. For instance, the perforation 100 is prolonged as 45 indicated by the dotted line 103 so that the note thereof, once sounded by the perforation 100, will be continuously sustained throughout an arbitrary period and until its sounding is terminated to provide for a re-sounding by the perforation 104. The latter 50 is also arbitrarily prolonged to sustain its note. The combined lengths of the perforations 100, 103 and 104, 107, indicate, by way of illustration, a period of time in the travel 55 of the note sheet during which it is desired to sustain notes of the first group to reproduce or imitate a sustaining pedal effect.

The illustrative hiatus between the prolongation 103 and the perforation 104 is intended merely to provide for a second dis-

tinct percussion of the corresponding string which is desired to occur in the playing; and this hiatus is preferably so brief that it is little if any appreciated by the hearer, the result being to all intents and purposes that 70 the note initially sounded by the perforation 100 is sustained throughout the desired period of the pedal effect, the re-sounding of the note of the perforation 104 being introduced in accordance with the tempo of 75 the original record.

In like manner, a perforation 101 having its advance end located in proper relation to the advance of the other perforations, to produce the tempo of the original record, 80 has a prolongation 102 to sustain the note until terminated preparatory to re-sounding the same by the perforation 106 which has also a prolongation 108 which terminates preparatory to re-sounding the note by a 85 perforation 109 having a prolongation 110. Thus the perforations 101, 102, 106, 108, 109 and 110 sound and sustain and re-sound their notes with substantially the tempo effect indicated by the original record, when 90 accompanied by a sustaining pedal operation.

A perforation 111 sounds its note in the proper tempo relation to the others, and that note is sustained by a prolongation 112 extending throughout the distance corresponding to the period during which the sustaining pedal effect is desired to be maintained.

The foregoing will suffice to illustrate to those skilled in the art, a construction of note 100 sheet embodying this invention. The specific illustration of the drawings represents a practicable arrangement of perforations and prolongations.

It will be noted that these sustaining effects are produced by the individual note perforations whereby the specific notes are themselves sustained and such sympathetic harmonious vibrations occur in such other strings as are undamped at the time, while 110 on the other hand, the discordant sympathetic vibration is eliminated, thereby avoiding an objection to the normal damper pedal operation.

Whether or not any deliberate variation in 115 intensity is provided for upon the sheet, by informative symbols or otherwise, the sustaining effects above described give, in actual playing, an effect of light and shade, as it were, in intensities upon many types of playing instruments.

For example, when many notes are being sustained in the unique manner provided for by the prolongations of a large proportion of the individual note perforations, each 120 pneumatic playing action which is employed in so sustaining a note, continuously bleeds from the supply of pneumatic pressure or exhaust and thereby tends to reduce such pressure or exhaust with a tendency to 125

- cause succeeding notes to be sounded more softly. This tendency is, of course, increased as a greater number of notes are sustained and the effect is enhanced, to such 5 extent as to be readily appreciable, by the use of the extensive note sustaining prolongations or perforations, overlapping in many cases, as illustrated in the drawing. While this effect of light and shade in intensity 10 does not necessarily follow the variations in intensity which may be indicated upon the original record, it nevertheless serves substantially and valuably to eliminate the practically uniform intensity of playing which 15 contributes to the monotonous mechanical quality which has characterized the playing by means of most note sheets heretofore used, and has invariably characterized the playing of note sheets having no supplemental intensity or pedal perforations by which to 20 operate auxiliary expression controlling mechanism. In other words, this invention presents for the first time in the art an arrangement of perforations in a note sheet by 25 which sustaining pedal effects are produced and at the same time the monotonous intensity of playing is eliminated—all by means of individual note perforations and without the employment of any automatic 30 mechanism except the individual note sounding actions.

It is to be understood that the invention is not limited to the specific details of the described illustrative note sheet construction. 35 On the contrary, as will appear to those skilled in the art, the invention may be variously embodied.

Claims:

1. A note sheet for reproducing or imitating characteristics of a manual rendition, 40 provided with note sounding perforations which have their advanced ends relatively located to sound their notes in accordance with desired tempo, but which, in order to

cause their notes to be sustained with the 45 effect of a damper pedal operation, have their rear ends arbitrarily prolonged.

2. A note sheet for reproducing or imitating characteristics of a manual rendition, provided with note sounding perforations 50 which have their advanced ends relatively located to sound their notes in accordance with desired tempo, the length of some of said perforations being that called for by the noted tempo value of the notes controlled thereby, while the length of others of said perforations differs from that called for by the noted tempo of the notes controlled thereby, by being prolonged beyond that called for by said noted tempo, whereby the 55 strings of the notes controlled by the perforations thus prolonged are maintained undamped and said notes are individually sustained with the effect of a damper pedal operation.

3. A note sheet for reproducing or imitating characteristics of a manual rendition having perforations therein for sounding respective notes, with their advance ends relatively located to sound the notes in accordance with desired tempo, a large proportion of perforations selected from said perforations being arbitrarily prolonged, the prolongations of perforations corresponding to notes in a given musical measure of the 75 composition to be played, being substantially overlapped whereby said prolongations combine to sustain their respective notes concurrently with an effect of a damper pedal operation.

In testimony whereof, I have signed my name to this specification in the presence of two subscribing witnesses.

CHARLES F. STODDARD.
